KARL BAUMANN, OF URMSTON, ENGLAND, ASSIGNOR TO THE BRITISH WESTINGHOUSE ELECTRIC AND MANUFACTURING COMPANY LIMITED, A CORPORATION OF GREAT BRITAIN.

CONDENSING STEAM-TURBINE PLANT.

1,304,144.

Specification of Letters Patent. Patented May 20, 1919.

Original application filed March 25, 1916, Serial No. 86,777. Divided and this application filed September 22, 1917. Serial No. 192,801.

To all whom it may concern:

Be it known that I, KARL BAUMANN, a citizen of the Confederation of Switzerland, and a resident of Urmston, in the county of 5 Lancaster, England, have made a new and useful Improvement in Condensing Steam-Turbine Plants, of which the following is a specification.

This is a division of my application filed 10 March 25, 1916, Serial No. 86,777 and like said application relates to plants for producing power, comprising a steam generator, a main steam turbine, a condenser, a feed water heater and their usual and appropriate auxiliaries, and with or without an economizer for conserving the heat of flue gases, and has for its object to provide an improved arrangement and construction of power plant of this kind whereby the 20 overall efficiency is increased as compared with existing plants.

This object I attain, according to this invention, by utilizing the steam given off from the water sealed glands of the main 25 turbine and the steam which leaks past the balance pistons thereof, for heating the feed water instead of as has heretofore been the practice, of exhausting said steam directly into the condenser or to an intermediate 30 point in the low pressure end of the turbine. Such steam as is here utilized is at a comparatively low pressure and the feed water heater or heaters in which it is utilized operate at a pressure below atmospheric.

In this case, in which the turbine is provided with balance pistons and water sealed glands in which the mechanical work expended on the sealing water by the paddle 40 wheel of the gland vaporizes a certain amount of water which appears as steam which enters the lantern space of the gland, it is advisable to use two heaters, preferably arranged to operate in series.

45 In operating arrangements of the above kind, it sometimes happens that the extraction pump of the main condenser discharges its water intermittently, with the result that the leakage steam from the balance pistons 50 or the steam from the water sealed glands, is not fully condensed in the feed water heater or heaters into which it is led. To obviate this, a by-pass is provided for leading away to the main condenser or turbine

exhaust or any other suitable stage of the 55 main turbine, any leakage steam from the balance pistons or steam from the water sealed glands which may accumulate due to non-condensation in the heater or heaters. Said by-pass is provided with a back pressure valve or is otherwise so arranged as to prevent steam passing to the condenser, the turbine exhaust or an operative stage of the main turbine, except when the pressure of 60 said steam rises above a determined pressure.

If desired, said by-pass may take the form of a siphon tube containing water, forming a seal, which in the event of the pressure of the steam rising above a determined pressure, will be blown out, permitting the steam to pass to an intermediate stage of the turbine or to the condenser or turbine exhaust. Suitable valves will be preferably provided in the siphon tube to enable the same to be 70 refilled with water during operation of the plant.

The accompanying sheet of drawing diagrammatically shows an arrangement for carrying out the present invention.

In this view a main turbine 2 of the reaction type is provided with balance pistons 3 and 4 for the intermediate and low pressure sections respectively, and water sealed glands provided with rotatable runners 5 and lantern space 6 prevent leakage of steam from the turbine casement around the turbine shaft.

The turbine is connected to a condenser 7 in the usual manner, and the condensate is 90 drawn off through pipe 8 by extraction pump 9 and forced through feed water heaters 10 and 11 arranged to operate in series. The feed water is led away from feed water heater 11 by pipe 12 to an economizer or to 95 a hot well from which it is delivered to the steam generator of the system.

The feed water in heater 10 is heated by steam from the water sealed gland at the left of the turbine and by steam leaking 100 past balance piston 4, such steam being led to heater 10 through pipe 13.

Heater 11 which is connected in series with heater 10 is supplied through pipe 14 with steam leaking past balance piston 3. 105 The heater 11 is connected by pipe 15 with a point in the turbine at which the pressure is approximately equal to that existing in

front of balance piston 4. A non-return valve 16 is located in pipe 15 to prevent steam from the operative part of the turbine flowing through the pipe 15 to the 5 heater 11. A back pressure valve may also, if desired, be provided in the pipe 15, though this will in many cases be found unnecessary.

In this arrangement it will also be necessary to slightly raise the pressure behind 10 balance piston 4, that is, to the left of the piston, and, if desired, make said piston slightly larger for the purpose of avoiding unbalanced end thrust, occasionally by the 15 fact that it is desirable to increase the pressure of the steam delivered to the heater so that its temperature will be slightly above that to which it is desired to heat the water.

Pipe 17 containing a back pressure valve 20 connects the heater 10 to the condenser 7. The function of said back pressure valve, as hereinbefore explained, is to prevent steam passing from the heater to the condenser, or 25 turbine exhaust except when the pressure of steam in the heater rises above a determined pressure, by reason of insufficient condensation therein.

A drain pipe 19 of small dimensions leads from the outlet of heater 11 to the condenser 30 and through this, water and non-condensable gases accumulating in the heater may escape to the condenser.

The invention herein set forth is not restricted to condensing steam turbine plants 35 including an economizer or economizers utilizing the heat of the flue gases, as it may equally well be applied to plants not provided with an economizer, such for example, as condensing steam turbine plants installed 40 on marine vessels. The two feed water heaters or their equivalents, need not necessarily be operated in series, but series operation is preferred to parallel operation.

Having thus described my invention what 45 I claim is:

1. In combination with a steam turbine, two feed water heating means operating in series and below atmospheric pressure, means for delivering leakage steam from 50 the turbine to each of said heating means and means for discharging non-condensable gases from said heating means.

2. In combination with a steam turbine having water sealed glands, feed water heating means operating below atmospheric pressure, means for delivering steam from 55 said glands to said heating means and means for discharging non-condensable gases from said heating means.

60 3. In combination with a steam turbine having balancing pistons, feed water heat-

ing means operating below atmospheric pressure, means for delivering steam leaking past said balancing pistons to said heating means and means for discharging non-condensable gases from said heating means.

4. In combination with a steam turbine having balancing pistons and water sealed glands, two feed water heating means operating in series and below atmospheric pressure, means for delivering steam from said glands and leakage steam from said balancing pistons to one of said heating means, means for delivering leakage steam of higher pressure to the other of said heating means and means for discharging non-condensable gases from said heating means.

5. In combination with a turbine having a balancing piston and water sealed glands, feed water heating means adapted to operate below atmospheric pressure, a condenser, a connection between said heating means and said condenser and means for delivering steam from said glands and steam leaking past said balancing piston to said heating means.

6. In combination with a steam turbine, feed water heating means comprising at least two units operating in series below atmospheric pressure, means for delivering leakage steam from the turbine to one unit of the heating means, means for delivering steam from the turbine to another unit of the heating means and means for discharging non-condensable gases from said heating means.

7. In combination with a steam turbine, two feed water heating means connected to operate in series and below atmospheric pressure on leakage steam delivered from the 1 turbine, means for delivering steam from said heating means to a working stage of the turbine, and means for discharging non-condensable gases from said heating means.

8. In combination with a steam turbine, a condenser, connected to the exhaust thereof, water sealed glands for the turbine shaft, balancing pistons for the turbine rotor, a multi-stage feed water heating means, the stages of which are adapted to operate in 1 series and below atmospheric pressure, a connection between said heating means and said condenser and means for delivering steam from non-power producing portions of said turbine to said heating means.

In testimony whereof, I have hereunto subscribed my name this eighth day of August 1917.

KARL BAUMANN.
